UNITED STATES PATENT OFFICE.

CHARLES F. NORDEN, OF NEW YORK, N. Y., ASSIGNOR TO HENRY HYMAN & CO., INC.,
OF NEW YORK, N. Y., A CORPORATION OF NEW YORK.

SWITCH WITH TIMING DEVICE.

Application filed July 19, 1920. Serial No. 397,326.

To all whom it may concern:

Be it known that I, CHARLES F. NORDEN, a subject of the Republic of Germany, residing at New York city, in the county of New 5 York and State of New York, have invented a new and useful Improvement in Switches with Timing Devices, of which the following is a full, clear, and exact description.

My invention relates to time switches, the 10 object of the invention being to maintain the current to apparatus controlled by snap switches, push button switches, knife switches, sockets and flash light switches for an adjusted time interval after the switch is 15 turned off.

I attain these objects by the mechanism illustrated in the accompanying drawing, in which are shown the arrangements of the wiring and mechanism of the switch.

20 Fig. 1 is a diagrammatic illustration of the invention with the circuit open and the switch off; Fig. 2 is a diagrammatic illustration showing the circuit closed; Fig. 3 is a diagrammatic illustration showing the main 25 circuit device turned off but with the shunt circuit through the timing mechanism closed; and Fig. 4 is a diagrammatic illustration of the apparatus at the moment that the timing mechanism is releasing the time 30 circuit device.

Similar numerals refer to similar parts throughout the several views.

The circuit closing device or main switch for the main circuit has a carrier or pin 2 arranged to contact with a second circuit closing device or supplemental element 3 and move it against the pressure of spring 4 into closed position as the main switch is closed, a catch or link 5 on the end of a 35 thermostatic spring 6 engaging the end of the supplemental element 3 to hold it in closed position. A screw 7 is provided to bend the thermostatic member 6 to adjust the extent of engagement between the contacting faces of member 3 and the hook 5.

40 A resistance wire 8, preferably of German silver and of a resistance suitable for the current to be carried, is wound upon or near the thermostatic spring 6. One end of this 45 resistance wire 8 is connected to the spring 6 and the other connects to the main circuit between the contact 9 and the lamp 10.

50 A contact 11 arranged to be engaged by the member 3 when in closed position is 55 connected to the thermostatic member 6.

When the main switch is closed, the parts are moved from the position of Fig. 1 to that of Fig. 2, the pin 2 moving member 3 into closed position with the hook 5 engaging its end. The lighting current now 60 passes through member 1 and contact 9 to the lamp, substantially no current passing through the shunt circuit formed by member 3, contact 11, spring 6 and resistance wire 8. When the main switch member is 65 opened, the hook 5 retains the member 3 in its closed position, but now the lighting current may pass through the former shunt circuit to the lamp. This heavier current heats the resistance 8 and the thermostatic 70 spring 6 to cause it to bend to withdraw the hook 5 and release member 3, whereupon spring 4 moves member 3 to open the circuit and extinguish the lamp 10. The spring 6 now cools and returns to its normal 75 position, ready to engage member 3 when the main switch is next closed.

By adjusting the screw 7, the end of the spring 6 may be shifted to vary the extent to which the hook 5 overlaps the end of the member 3. This serves to vary the time 80 between the opening of the main switch and the release of the supplemental member 3 and therefore the time the lamp 10 will continue to burn after the main switch is 85 opened.

I claim:

1. In a thermostatically-controlled time switch, a main circuit, a pivoted main switch for opening and closing a break in 90 said main circuit, a supplemental pivoted switch having its plane of motion parallel to said main switch and having a bias to open position, means to move said supplemental switch to closed position when the 95 main switch is closed, a thermostatic latch member comprising a curved sheet metal spring fastened at one end and having a hook at the opposite end adapted to engage and hold the supplemental switch in closed 100 position, said spring extending in the plane of motion of said supplemental switch, and a shunt circuit having a part arranged to heat said latch member to cause it to bend to release its hook from engagement with 105 said supplemental switch when said main switch is open.

2. In a thermostatically-controlled time switch, a main circuit, a pivoted main switch for opening and closing a break in 110

said main circuit, a supplemental pivoted switch having its plane of motion parallel to said main switch and having a bias to open position, means to move said supplemental switch to closed position when the main switch is closed, a thermostatic latch member comprising a curved sheet metal spring fastened to one end and having a hook at the opposite end adapted to engage and hold the supplemental switch in closed position, said spring extending in the plane of motion of said supplemental switch, a shunt circuit having a part arranged to heat

said latch member to cause it to bend to release its hook from engagement with said supplemental switch when said main switch is open, and means to adjust the position of said hook in relation to said supplemental switch to regulate the time of operation of the shunt circuit before the supplemental switch is released.

Signed at New York city, N. Y., this 15th day of July, 1920.

CHARLES F. NORDEN.

Witness:

ANTHONY LAMANTIA.
